UNITED STATES PATENT OFFICE.

WILLIAM CROOKS, OF ALDRICH, ALABAMA.

AUTOMATIC MINE-DOOR-OPERATING MECHANISM.

1,345,074.

Specification of Letters Patent. Patented June 29, 1920.

Application filed July 17, 1919. Serial No. 311,633.

To all whom it may concern:

Be it known that I, WILLIAM CROOKS, a citizen of the United States of America, residing at Aldrich, in the county of Shelby

5 and State of Alabama, have invented certain new and useful Improvements in Automatic Mine-Door-Operating Mechanism, of which the following is a specification.

10 My invention relates to an automatic mine door operating mechanism in which the cars are adapted to control automatically the opening of the doors which are so hung as to be self closing.

15 One object of my invention is to simplify and perfect the mechanism whereby the mine car or motor will act automatically to open the doors.

20 A further object is to perfect a novel means for suspending outwardly sliding self closing doors so as to avoid interference with the overhead electric trolley wire in electrically operated mines.

25 A further object is to provide the door opening arms, which are spaced apart by the oncoming car or locomotive, with yielding inwardly disposed straps which make sure that the doors will be pressed far enough apart to clear any part on the car.

30 My invention also comprises the novel details of construction and arrangements of parts, which in their preferred embodiments only are illustrated in the accompanying drawings, in which:—

35 Figure 1 is an elevation showing the mine doors in closed position.

40 Fig. 2 is an enlarged plan view of the telescoping rods utilized to open the door and showing their equipment with spring resistance straps.

45 Fig. 3 is a diagrammatic plan view showing the operating mechanisms on both sides of a pair of doors.

Similar reference numerals refer to similar parts throughout the drawings.

50 As illustrated, the mine cars 1 are adapted to travel on the mine track 2 and at suitable intervals the mine is equipped with transversely movable pairs of doors 3, the doors being suspended overhead by hangers 4 and

55 trolleys 5 from inclined tracks 6 which slope upwardly and outwardly from the center line above the track. The doors at their lower ends travel between guide bars 7 attached at their outer ends to suitable supports and at their inner ends, which curve downwardly at 8, to a conveniently placed

cross tie 9. These guides have the same slope as the overhead track 6 and the doors are thus suspended free to travel on their hanger supports.

60 Where the mine haulage is electric, it is necessary to modify one of the hangers and to this end, as will be seen in Fig. 1 where the trolley wire 10 is shown, the adjacent hanger is formed by an elongated metal strap 11 which extends upwardly and is bent so as to have a U-shape in elevation with the trolley wheel 5 journaled at the free end of its upper leg. It must be apparent that the U-shaped hanger will straddle the trolley wire and will not interfere with it as the door slides back and forth in response to the mechanism which will now be described.

65 At each side of the track and, where traffic is in both directions, on both sides of the doors, I provide suitable fixed blocks or supports 12 which preferably rise to a height of from 14" to 16" above the track and are securely anchored. Upon the top of each 70 of these blocks or supports is mounted a metal strap 13 under which the flattened end 14 of a pipe 15 is passed with a pivot bolt 16, passing through the strap and pipe end 14 so as to pivotally connect it to the block. 75

80 In the free end of the pipe I telescope a rod 17 which at its outer end is pivotally connected by a metal strap or plate 18 to the inner edge of the adjacent mine door. A curved resistance strap 19 of spring metal 85 has one end riveted or otherwise attached to the free end of its respective pipe 15 and at its other end is bent under and back and held under a strap or band 20 which surrounds the pipe. As shown in Fig. 2 these resistance 90 straps face away from the doors and are disposed to be engaged by the oncoming mine car or locomotive and to absorb or take care of the initial thrust like a spring buffer to avoid too great a strain on the door 95 operating mechanism if the car or locomotive is moving faster than is proper as it approaches the doors to be opened.

100 This invention is not intended to be restricted in scope to the specific embodiments shown, but contemplates such modifications as come within the spirit and scope of the claims.

105 Having thus described my invention, what I claim as new and desire to secure by Letters Patent, is:—

110 1. In a mine door opening mechanism, a

pair of laterally moving sliding doors, side anchors, and divergent telescoping arms connected at one end to the pair of doors and at the other end to said side anchors.

5 2. In a mine door opening mechanism, a pair of laterally moving sliding doors, side anchors, divergently disposed telescoping arms connected at one end to the pair of doors and at the other end to said anchors, 10 and a pair of spring buffers carried by the arms and located near said doors and disposed in the path of an on coming door opening car.

3. In combination with a pair of mine 15 doors, upwardly and outwardly inclined transverse tracks, trolley hangers movable on said track by which said doors are suspended, bottom guides between which the doors slide freely, a pair of car operated 20 divergent horizontally swinging arms connected at their free end to said doors near their adjacent edges, and fixed bearings to which the other end of said arms are pivoted.

25 4. In combination with a pair of mine doors, upwardly and outwardly inclined transverse tracks, trolley hangers movable on said track by which said doors are suspended, bottom guides between which the 30 doors slide freely, a pair of car operated di-

vergent horizontally swinging arms connected at their free end to said doors near their adjacent edges, and fixed bearings to which the other end of said arms are pivoted, one of said hangers being U-shaped to straddle 35 an overhead electric conduit as the door moves back and forth.

5. In combination with a pair of laterally movable mine doors and their supports, of pivoted arms having their free ends adjacent to the meeting edges of said doors, members pivotally connected to said doors and slidingly connected to the free ends of 40 said arms, and a curved spring plate made fast at the free end of each arm and disposed to face inwardly to form a yielding 45 buffer adapted to receive the impact of the oncoming door opening car.

6. In a mine door operating mechanism, laterally sliding doors, supports therefor, divergent opening arms projecting from the meeting edges of the doors outwardly, pivotal supports for the outer ends of said arms, and spring members on the arms which project inwardly substantially into line with 50 the meeting edges of the doors.

In testimony whereof I affix my signature.
WILLIAM CROOKS.
